UNITED STATES PATENT OFFICE.

WILLIAM G. HARTWIG, OF CHICAGO, ILLINOIS, ASSIGNOR TO RAILWAY UTILITY COMPANY, OF CHICAGO, ILLINOIS, A CORPORATION OF ILLINOIS.

ELECTRIC HEATER FOR STREET CARS AND THE LIKE.

Application filed April 26, 1924. Serial No. 709,085.

To all whom it may concern:

Be it known that I, WILLIAM G. HARTWIG, a citizen of the United States, residing at Chicago, in the county of Cook and State 5 of Illinois, have invented certain new and useful Improvements in Electric Heaters for Street Cars and the like, of which the following is a specification.

My invention relates more particularly to 10 electric heaters to be attached to the truss planks of passenger cars, i. e. along the sides of a car a short distance above the floor. The object of the invention is to provide a housing and mounting for electric heating elements, adaptable to the above mentioned 15 location and support which is slightly, durable under the conditions to which it is subjected in such location, efficient in utilizing the heat developed by the element and safe 20 both with respect to the support on which it is mounted and the heating elements itself. My improved housing and support comprises a casing perforated for the passage of air and a baffle plate on which the heating 25 element is mounted and which is so arranged as to provide for the passage of a current of air between the same and the truss plank on which the casing is mounted, the heating element being mounted on the 30 baffle, as a consequence of which arrangement that portion of the heat given off by the heating element which is transmitted to its support is taken up by the current of air and supplied to the interior of the car instead of being transmitted to the outside of 35 the car as in similar constructions of the prior art.

In the drawings, accompanying and forming 40 a part of the specification, Figure 1 is a perspective view of a truss plank heater embodying my invention; Fig. 2 a transverse section on the plane of the line 2—2 of Fig. 1; Fig. 3 a vertical longitudinal section through the housing showing the heating 45 element and its connections in elevation, the construction being shown as broken away in order to condense the figure; Fig. 4 is a horizontal section partly in elevation, on an enlarged scale of a detail showing an end of 50 the heater; Fig. 5 is a vertical section on an enlarged scale on the plane of the line 5—5 of Fig. 1; Fig. 6 is a perspective, partly broken away, of a somewhat different form of the invention; Fig. 7 a front elevation of 55 one end of the same; and Fig. 8 a transverse

vertical section on the line 8—8 of Fig. 7. Each part is identified by the same reference character wherever it occurs in the several views.

In the drawings, I have shown my invention in connection with a known form of electric heating element found upon the market, but it is to be understood that this form of heater per se is not of my invention and the invention may be used with 60 other forms of heating elements. The form of heater shown comprises a sheath or casing 6 of sheet metal enclosing a resistor wire or ribbon imbedded in insulating material, the ends of the wire or ribbon being attached 65 to terminal posts 7, one of which is shown in Fig. 4. The heating element is supported independently of the terminals by lugs or brackets 8 attached respectively to 70 insulating blocks 9 at the opposite ends of 75 the housing. As best seen in Figs. 4 and 5, the metal sheath 6 is collapsed at its ends beyond the resistor strip and filling and perforated at 10 for the passage of the 80 insulating sleeve 11 by which said sheath is 85 insulated from the screw bolt 12 by means of which it is mounted upon the bracket 8 above mentioned. The insulation of the bolt from the sheath is completed by insulating washer 13 and a metal washer 14 is 90 placed between the head of the screw and the insulating washer. The insulating sleeve 11 is formed with a broad flange, and intermediate said flange and the bracket 9, the screw bolt passes through a hole in 95 the end of a connector 15 by means of which the bracket is electrically connected to the terminal of the heating element. A nut 16 and nut lock 17 complete the structure 100 by which the heating element is mounted on the bracket 8. As best shown in Fig. 3, each bracket 8 is mounted on its insulating support by screws 18, one of which may serve for the lead wire which is connected thereby to the corresponding end of the 105 heater. While the heating element just described is satisfactory for the purpose, it forms no part of the present invention except as a part of the general combination, as as before mentioned other forms of heater elements may be substituted therefor.

The form of the invention shown in Figs. 1 to 5 inclusive is adapted to be secured to the truss plank and project outwardly into 110 the car. The bottom wall 19, front wall 20

and top wall 21 of the casing are preferably formed from a single sheet of metal suitably bent at the corners 22—23 thereof and likewise bent at 24—25 to form flanges 26, 27 by which said casing may be attached to the truss plank. The bottom and front walls are perforated at 28, 29 for the passage of air currents. The ends 30 of the housing are preferably formed of struck-up sheet metal and spot welded or otherwise secured to the main body thereof.

The above mentioned baffle 31 is L-shaped in cross section and of approximately the length of the housing and is mounted there-
15 in so that its vertical leaf 32 is spaced away from the truss plank on which the heater is mounted and the horizontal leaf 33 there-
of is spaced away from and parallel to the top of the casing. The bottom of the cas-
10 ing is formed with a series of holes 34 ad-
jacent the flange on the edge thereof, and the top of the front wall of the casing is formed with a horizontal series of holes 35 so that a free passage is afforded for air
20 from the holes in the bottom wall upwardly behind the vertical leaf of the baffle and then forwardly over the horizontal leaf of the baffle to the openings 35. Thus, the heat absorbed by the baffle 31 from the electric
25 heater is absorbed by the air currents pass-
ing back of and above the same so that said heat is utilized in heating the car and not transmitted to the truss plank where it would be wasted and further might overheat
30 and perhaps injure the plank. The baffle is supported at its ends by brackets 40 struck up out of sheet metal and secured to the baffle by the screws 41 by which the re-
35 spective insulating blocks 9 are secured to said baffle. As shown in Fig. 5, the screws are received in sockets 42 cast in the insulat-
40 ing blocks. The brackets are secured to the truss plank by screws 43 independently of the housing and are turned up at their outer
45 ends as at 44 to lie against the end walls of the housing. One of the end walls and the adjacent bracket are perforated as at 45 to serve as an outlet for the wires leading to the respective ends of the heating element.

50 The form of the invention illustrated in Figs. 6 to 8 inclusive is designed to seat within an opening cut in the truss plank with the face thereof substantially flush with the outer face of the plank. The casing comprises a top wall 50, a bottom wall 51, a rear wall 52, and end walls 53, the top, bottom and end walls being flanged as at 54 so that when the heater is seated in the opening in the truss plank the flanges 54 may be screwed to the adjacent edges of the opening. The face plate 55 is perforated as shown and secured at its edges over the flanges of the body portion of the casing.
55 The bottom wall 51 of the casing is per-
forated along its rear edge as at 56 but other-

wise the walls of said casing are imperforate.

In the specific illustration of the invention in the drawings Figs. 6 to 8, two electric heating elements 57 are used, being 70 mounted at their respective ends on common insulating blocks 58 by means of brackets 59, 60. Preferably the upper brackets 59 are bent outwardly so that the heating elements are in different vertical planes, there-
75 by increasing the heating effect. The insulating blocks above referred to are mounted on a guide or baffle plate 61 which is secured by screws 62 to the back of the hous-
80 ing. The baffle 61 is spaced from the rear wall of the housing by sleeves 63 and the upper end of the baffle is bent forwardly as at 64, the upper edge thereof resting in contact with the perforated front plate. Preferably the lower end of the baffle is bent 85 slightly forward as at 65. There is thus provided a free passage for air entering through the holes 56 in the bottom wall of the casing up behind and above the baffle plate to the outlet openings 68 at the top 90 edge of the front plate whereby the heat radiated or otherwise transmitted to the baffle is taken up and carried into the body of the car.

I claim:

1. An electric heater of the class described comprising a casing having a perforated front wall adapted to be secured to a vertical support, means within the casing for supporting an electric heater and a baffle 100 plate mounted within the casing and between the heating element and the casing support and spaced from the latter, there being perforations in the lower part of the casing 105 permitting the flow of air currents upward behind the baffle.

2. In a heater of the class described, a casing having a perforated front wall adapt-
110 ed to be attached to a vertical support, a heating element mounted within the casing and a baffle arranged to the rear of the heating element and spaced from the back of the casing and projecting forwardly above the heating element to permit currents of air to circulate back of and above the heating 115 element.

3. In an electric heater of the class de-
scribed, a casing having a perforated front wall adapted to be attached to a vertical wall, a vertical baffle mounted in the casing 120 and spaced from the back thereof and an electric heating element mounted on the baffle, there being openings in the lower and upper part of the casing communicating with the space back of the baffle to permit upward circulation of air therethrough.

4. In an electric heater of the class de-
scribed a casing having a perforated front wall adapted to be attached to a vertical wall or support, a baffle L-shaped in cross 130

section, and means for spacing the baffle from and mounting it upon the rear of the casing, there being openings in the lower and upper parts of the casing to permit the circulation of air back of the baffle.

5. In an electric heater of the class described, a casing perforated as to its bottom and front walls and imperforate as to its top wall, an L-shaped baffle mounted in the casing with one leaf thereof vertical and the other end horizontal and spaced from the top of the casing to provide an air passage along the back and top of the casing communicating at its ends with the perfora-

tions in the front and bottom walls and an 15 electric heater mounted on the baffle.

6. An electric heater of the class described, a casing having an imperforate top wall and perforated front and bottom walls, an L-shaped baffle arranged in the casing 20 with one leaf thereof parallel to and spaced from the bottom of the top wall and the other leaf parallel to and spaced from the rear wall, an electric heater mounted on the baffle and brackets supporting the baffle in- 25 dependently of the casing.

WILLIAM G. HARTWIG.
